UNITED STATES PATENT OFFICE.

WILLIAM S. HOLDAWAY, OF PROVO, UTAH, ASSIGNOR TO THE H. & S. PUMP COMPANY,
A CORPORATION OF UTAH.

PUMP.

1,191,423.

Specification of Letters Patent. Patented July 18, 1916.

Application filed January 15, 1913. Serial No. 742,254.

To all whom it may concern:

Be it known that I, WILLIAM S. HOLDAWAY, a citizen of the United States, residing at Provo, in the county of Utah and State of Utah, have invented a new and useful Pump, of which the following is a specification.

The invention relates to pumps particularly designed for forcing liquid, the device being of such a construction as to be also 10 useful as a compressor.

One of the objects of the invention is to employ interfitting opposed screw conveyers which coöperate to trap independent bodies of fluid and to force said bodies longitudinally within the pump casing from the inlet to the outlet thereof.

A further object is to provide forcing means which operate positively to prevent the liquid under compression or being elevated, from flowing backwardly, the pump, as a result, being maintained primed under all conditions.

With the foregoing and other objects in view which will appear as the description 25 proceeds, the invention resides in the combination and arrangement of parts and in the details of construction hereinafter described and claimed, it being understood that changes in the precise embodiment of the 30 invention herein disclosed, can be made within the scope of what is claimed, without departing from the spirit of the invention.

In the accompanying drawings the preferred form of the invention has been shown.

35 In said drawings:—Figure 1 is a plan view of the pump, the top of the casing being removed. Fig. 2 is a front elevation of the pump. Fig. 3 is a section on line A—B Fig. 1.

40 Referring to the figures by characters of reference 1 designates a casing preferably made up of separate sections each of which extends throughout the length of the pump, the said sections being flanged, as at 2, and 45 bolted or otherwise connected so as to prevent leakage therebetween. Journalized within the heads or ends of the casing are shafts 3 and arranged on each of these shafts and within the casing are oppositely disposed

50 similar screws 4 so shaped and proportioned that the convolutions of each screw will fit snugly between the convolutions of the other screw and extend up to the core or center of the screw. This has been clearly indicated 55 in Fig. 1. The casing 1 fits snugly around

the screws and up to the points on the peripheries thereof where said peripheries intersect, as shown in Fig. 3. Gears 5 are secured to the shaft 3 and are of the same size and constantly in mesh. Thus it will be seen 60 that the two screws will rotate at the same speed and in opposite directions and, consequently, separate compartments will be formed between the convolutions of each screw, as shown at 6, each compartment being 65 constantly out of communication with the other compartments, such communication being cut off by the adjacent convolution of the opposed screw.

It will be noted that one of the heads of 70 the casing has thrust bearings which engage the ends of the shafts, thus relieving the head from all thrusts which might be exerted thereagainst by the screws, thereby preventing undue wear upon the heads and also 75 permitting the pump to operate with less power than would otherwise be necessary.

An inlet 7 may be provided at one end of the casing and an outlet 8 at the other end thereof. Power may be transmitted to either 80 of the shafts 3 and it will be apparent that when said shaft is rotated in one direction, the gears 5 will cause the other shaft to rotate in the opposite direction. Thus any fluid which may enter the inlet 7 and the 85 compartments 6 registering therewith, will be forced longitudinally within the casing by the rotating screws and ultimately expelled through the outlet 8. As the compartments are at all times out of communication 90 with the remaining compartments in the casing, it will be apparent that the fluid, after once passing between the convolutions of the screws, cannot be forced backwardly but necessarily travels toward the outlet as 95 the screws rotate. Furthermore leakage is practically prevented for the reason that any fluid escaping from the compartments nearest the outlet 8 will necessarily flow into the next adjoining compartments and as these 100 compartments are likewise filled, it will be seen that all of the compartments except those nearest the inlet are sealed.

It will be apparent that the device herein described not only constitutes an efficient 105 means for forcing fluid to a desired elevation, but can also be used effectively as a compressor.

What is claimed is:—

A pump including a casing having sockets 110

in one head thereof constituting thrust-bearings, parallel shafts journaled within the heads of the casing and bearing against and engaging said thrust bearings, a screw secured to and revolvable with each shaft, the threads of one screw fitting snugly between the convolutions of the threads of the other screw, both screws extending up to said head, said thrust bearings coöperating with 10 the ends of the shafts to relieve the head against thrusts from the screws, gears secured to the respective shafts and constantly meshing whereby the shafts are revolvable in opposite directions synchronously, said gears 15 being interposed between the screws and the

other head of the casing, the casing and screws forming separate non-communicating compartments between the convolutions of each screw, the screws and gears being completely housed in the casing, there being an 20 inlet at one end of the casing and an outlet at the other end thereof.

In testimony that I claim the foregoing as my own, I have hereto affixed my signature in the presence of two witnesses.

WILLIAM S. HOLDWAY.
